UNITED STATES PATENT OFFICE.

GEORGE ARTHUR SMITH, OF SEATTLE, WASHINGTON.

COLLAR-SUPPORTER.

1,179,772.

Specification of Letters Patent. Patented Apr. 18, 1916.

Application filed July 21, 1914, Serial No. 852,145. Renewed November 22, 1915. Serial No. 62,918.

To all whom it may concern:

Be it known that I, GEORGE ARTHUR SMITH, a citizen of the United States, residing at Seattle, in the county of King and State of Washington, have invented certain new and useful Improvements in Collar-Supporters, of which the following is a specification.

My invention relates to collar supporters and has for its object the provision of simple and convenient elastic devices to encompass the neck-band of a linen collar and retain the front edges or forwardly positioned extremities in close relation and in the neat and pleasing manner prescribed by present customs.

A further object of the invention is the provision of apparatus for securing a necktie to said elastic device and in operative condition with relation to the collar, so that the necktie may be adjusted freely without binding or unnecessary strain; a further object of the invention being to relieve the necktie of the duty of holding the collar ends together and causing such function to be performed by the elastic tape device above referred to, whereby the necktie may be arranged with more pleasing effect and without undue wear thereon.

In the drawings annexed hereto and in the following specification, a single embodiment of my invention is shown and described, although obviously, various changes and modifications of a useful character may be made within the scope of the claim without departing from the purpose or spirit of the invention.

The invention consists in the novel construction of collar supporting devices, and the combination and adaptation therewith of necktie holding apparatus, as will be fully described in the following specification, illustrated in the accompanying drawings, and finally set forth in the appended claim.

In said drawings, Figure 1 is a perspective view of the collar-supporting and necktie-holding devices embodying my invention arranged in operative condition with a necktie, with the collar to which they are adapted to be attached, removed. Fig. 2 is a cross-sectional view of the same shown attached to a turn-over collar also shown in section. Fig. 3 is a detached perspective view of the tie-holding slide.

Referring to said views, the reference numeral 1 indicates a strip of elastic tape or

other suitable material of relatively narrow width which is provided at one of its ends with a hook member 2 and at its opposite ends with an eye-member 3 having an eye 5 adapted to be engaged by said hook member to retain the said strip in annular condition. One end of said strip is provided with a loop formed by doubling back an extremity of the strip material and securing it to the body of the strip by means of sliding buckle 6 whereby said strip may be adjusted to various lengths, as will be well understood. Said looped end of the strip may be provided with a scale graduated in inches and half-inches, indicating the distance of such graduated marks from the opposite end of the tape and indicating by numerals 7 the lengths at which the strip should be adjusted to be worn with the various standard sizes of collars, respectively.

The strip member is adapted to encircle exteriorly, the neck-band portion 10 of a collar 11 and between the folds of the same. The collar is adjusted upon the shirt in the usual manner and the elastic strip positioned thereabout under sufficient tension to cause the tape to draw the front ends of the collar together and retain the front flaps of the collar in close relation. In this manner the clasp members 2 and 3 are hooked together. Intermediate said ends of the elastic strip may be attached thereto, one or more slides adapted to retain said strip in proper position relative to the collar and also to afford a sliding holder for a necktie T at the rear of the collar. Said slides each consist in a plate 12 formed with duplex apertures 13 divided by projections 14 between which are arranged a space whereby the strip may be threaded into said apertures 13 in order to position or remove the slide upon or from the strip without threading the latter through said apertures. At the lower portion of said plate a hook 17 is bent inwardly and upwardly, whereby the plate may be readily connected to the bottom edge of the neck-band of a collar, as indicated in Fig. 2. At the upper and lower edges of said plate there is also provided outturned and vertically arranged hook members 18 and 19 extending in opposing relation to receive the necktie therebetween. When such slides are connected to the elastic strip and then connected through the hook 17 with the collar, it will be seen that the strip is thereby secured at its rear intermediate portion in flat

spaced vertical relation at the rear of the collar, said hook member 17 being provided with sufficient resiliency to hold itself in adjusted position with the collar.

5 Before the collar is mounted upon the shirt, the necktie is positioned within the hook members 18 and 19 of each of the slides and when the collar is mounted upon the shirt in operative condition, the necktie is thus similarly held in adjusted relation to the collar and may be adjusted longitudinally with ease, as its engagement within the hooks 18 and 19 is relatively loose.

10 The tie can be fastened at its front portion in any manner desired and without placing any undue strain thereon as the tension of the collar is relieved therefrom and placed upon the elastic strip 1. Therefore, the tie will be held in operative condition with much 15 better effect than without the use of the slide and elastic strip and with less wear and tear on the delicate fabrics from which they are usually made.

20 The invention is simple and economical

to manufacture and convenient to put on, 25 and unobtrusive to wear and is believed to be a considerable advance in the art to which it pertains.

Having described my invention, what I claim, is—

30 In a device of the class described, a tie and collar support and guide formed of a blank having a central opening, opposed inwardly-directed lugs carried by the end walls of the opening and spaced apart at their ends, the lower end of the blank having a struck out portion with said struck-out portion and main body portion bent in opposite directions to provide a pair of guides of equal length, and a hook formed on the upper end 35 of the blank in alignment with one of the lower guides.

Signed at Seattle, Wash., this 3rd day of July 1914.

GEORGE ARTHUR SMITH.
